FIRE EXTINGUISHER METHOD AND APPARATUS

Harry Ensminger, Chicago, Ill., assignor to Cardox Corporation, Chicago, Ill., a corporation of Illinois

Application November 17, 1938, Serial No. 241,046

15 Claims. (Cl. 169—11)

This invention relates to new and useful improvements in methods and apparatus for producing and discharging fire extinguishing mediums.

5 The primary object of this invention is to provide a method and means for effecting discharge to the atmosphere of a plurality of low velocity, equal pressure, constant flow streams of gaseous and solid carbon dioxide to be used as a fire extinguishing medium.

10 A further important object of the invention is to provide a method and apparatus for converting liquid carbon dioxide, restrained under high pressure, into a mixture of solid carbon dioxide, 15 in the form of small particles and large flakes, and gas for use as a fire extinguishing medium.

15 Another object of the invention is to provide a novel form of discharge device for carbon dioxide to be used as a fire extinguishing medium.

20 A still further object of the invention is to provide in an ambulant fire extinguisher discharge device for carbon dioxide, means for obtaining a greater yield of snow than can be produced by merely permitting liquid carbon dioxide to expand as it is discharged to the atmosphere through a small orifice.

25 Other objects and advantages of the invention will be apparent during the course of the following description.

30 In the accompanying drawings forming a part of this specification and in which like numerals are employed to designate like parts throughout the same,

35 Figure 1 is a side elevational view of the apparatus embodying this invention.

Figure 2 is an end elevational view of the apparatus disclosed in Fig. 1.

40 Figure 3 is a fragmentary longitudinal sectional view taken on line 3—3 of Fig. 2.

Figure 4 is a fragmentary transverse sectional view taken on line 4—4 of Fig. 3.

45 Figure 5 is a longitudinal sectional view taken on line 5—5 of Fig. 2.

Figure 6 is a perspective view of a drum element which forms a part of the apparatus.

Figure 7 is a detail perspective view of a form of discharge guiding vane employed as a part of the apparatus, and

50 Figure 8 is an exploded view disclosing in perspective the two portions of a diffuser element.

55 In the drawings, wherein for the purpose of illustration are shown the preferred embodiments of this invention, the reference character 10 designates a pipe, of any desired length, which

is employed for connecting the discharge device embodying this invention to a source of supply of liquid carbon dioxide, preferably confined under high pressure within a container, or the like. A suitable source of supply would be from an uninsulated container which is subjected to the temperature of the surrounding atmosphere. It is to be understood that the pipe 10 is merely representative of means for connecting the discharge device to a source of supply. If desired, 5 a flexible hose may be substituted for the pipe 10 or the discharge device may be directly connected to the discharge end of a portable cylinder or drum.

The opposite ends of the pipe 10 are threaded, 15 as at 11 and 12. Connected to the threaded end 12 is a discharge head 13 which is formed with an internally screw threaded nipple 14 designed to receive the threaded end 12 of the pipe 10. A jam or lock nut 15 is employed for preventing 20 unintentional separation of the head 13 from the pipe. The wall 16 of the head 13, which separates the bore of the nipple 14 from the interior of the head is provided with a small or constricted orifice 17. This orifice functions as 25 an inlet opening for the interior 18 of the head 13. This interior functions as an expansion chamber. The nipple side of the wall 16 is of conical formation, as is indicated by the reference character 19, for effecting flow of the 30 liquid carbon dioxide toward the orifice 17 in a manner to prevent the formation of eddies and to insure smooth, high follow-up pressure discharge of the liquid carbon dioxide. The discharge side of the chamber 18; i. e., the outer 35 end of the head 13, is provided with an annular securing flange 20.

40 Detachably fastened to the outer face of the securing flange 20, by means of the screws 21, is the radially extending base flange 22 of an expansion drum 23, the construction of which is best illustrated in Figs. 2 to 6, inclusive. To prevent leakage between the discharge head 13 and the drum 23, a packing gasket 24 is positioned between the flanges 20 and 22.

45 This drum 23 is formed of sheet material and includes the cylindrical body portion 24 with the outer end wall 25 which is formed integral with the side wall. Longitudinally extending, circumferentially spaced slots 26 are formed in the cylindrical side wall 24 and extend into the end wall 25, as is clearly illustrated in Figs. 2, 5 and 6.

50 This drum 23, as is clearly illustrated in Figs. 3 and 5, is in open communication with the expansion chamber 18 of the discharge head 13 55

and forms with this chamber an expansion space or, more specifically, the drum acts as an extension of the expansion chamber 18.

For the purpose of diffusing the fluid discharged axially of the expansion chamber 18 and the interior of the drum 23 through the inlet orifice 17, and for deflecting this fluid outwardly through the slots 26, a diffuser 27 is provided. This diffuser is best illustrated in Figs. 5 and 8 10 as including a sleeve 28 having an end 29 received in the central aperture 30 of the end wall 25 of the drum 23. Fig. 5 discloses this end portion 29 of the sleeve as having been spun or flared outwardly and then brazed or welded, as 15 at 31, to the margin of the opening 30. The inner end of the sleeve 28 has inserted therein the reduced stem 32 of a pointed or conical head 33. This head is brazed or welded to the inner end of the sleeve 28, as at 34.

Fig. 7 discloses one of a series of elongated guiding vanes 35. This vane is of channel or rectangular formation in cross section. The longitudinal edges of the side walls 36 are cut away at 37 to form securing lugs 38 and 39. The inner 25 end 40 of the vane 35 is sloped or inclined inwardly so as to act as a closure for the inner end of the vane.

Figs. 3 and 4 best illustrate the fact that the vane 35 is secured to the peripheral surface 30 of the drum 23 by welding the lugs 38 and 39 to the cylindrical wall 24 of the drum, as at 41. The end wall 40 of the vane also is welded at 42 to the outer surface of the securing flange 22 of the drum. Figs. 2 and 5 clearly illustrate the fact 35 that one of these vanes 35 is provided for each discharge slot 26 of the drum 23. The vanes extend longitudinally with respect to the slots 26. Figs. 3 and 5 show the vanes 35 as being of proper length to position the outer securing lugs 38 at 40 the outer end portion of the drum 23 or so that the portions of the vanes extending beyond the securing lugs 38 project beyond the end wall 25 of the drum 23. Figs. 1, 2 and 3 disclose the cut-away edge portions 37 of the vanes which are 45 arranged between the securing lugs 38 and 39 as functioning to admit air from the atmosphere into the interiors or bores of the guide vanes.

The operation of and the method steps performed by the discharge apparatus described above will be explained as follows:

Liquid carbon dioxide flowing under high pressure through the bore of the pipe 10 is discharged through the constricted opening or orifice 17 into the expansion chamber 18. The liquid carbon dioxide is permitted to expand suddenly in the chamber 18 and is converted by this sudden expansion into a mixture of gas and small particles of solid carbon dioxide or carbon dioxide snow. 50 This mixture then flows axially of the expansion space formed by the chamber 18 and the interior of the drum 23 to be diffused and deflected radially outwardly through the several discharge slots 26 of the drum. In discharging through 55 these slots 26, the mixture impinges on the surfaces of the guide vanes 35 and is caused to make a sudden or sharp change in its direction of flow; i. e., from a radial direction through the slots 26 to a direction extending longitudinally 60 of the guide vanes. This impingement of the fluid discharged through the slots 26 and the sudden change in direction of flow each will function to produce or create large flakes of carbon dioxide snow and the collective result 65 of the impingement and the change in direction 70 75

of flow is the formation of a relatively high percentage of or yield of large flakes of solid carbon dioxide.

The velocity of the flowing fluid has been materially reduced by expansion within the chamber 18 and drum 23 and by its impingement against the vanes and the change in direction of travel. However, the velocity is still high enough to bring about the entrainment of air which is admitted through the cutaway portions 10 15 20 25 located between the securing lugs 38 and 39.

It will be appreciated, therefore, that the mechanism accomplishes three stages of discharge; first, the discharge through the constricted orifice 17 to permit expansion in the chamber 18 15 and the bore of the drum 23; second, the discharge through the longitudinally extending slots 26 in the expansion chamber drum 23; and, third, the impingement and change in direction of flow plus discharge of the resultant gaseous and solid 20 mixture to the atmosphere from the projecting ends of the guide vanes. The character of discharge, due to the areas of the several guide vanes being equal with respect to each other, is of a low final velocity and equal pressure and 25 provides a plurality of constant flow streams or jets of gaseous and solid carbon dioxide. This resultant discharge is very effective in extinguishing all types of fires.

It is to be understood that the form of this 30 invention herewith shown and described is to be taken as a preferred example of the same, and that various changes in the shape, size, and arrangement of parts may be resorted to without departing from the spirit of the invention or the 35 scope of the subjoined claims.

Having thus described the invention, I claim:

1. The method of employing carbon dioxide as a fire extinguishing medium which comprises discharging liquid carbon dioxide and constricting 40 said carbon dioxide at its discharge point, permitting sudden expansion of the discharged liquid to produce a mixture of gas and small particles of snow, dividing the mixture into a plurality of flowing streams, subjecting the mixture in said 45 streams to the shock of impingement and to a sharp change in its direction of travel to produce large flakes of snow, admitting air to the said flowing streams for entrainment by said mixture, and finally discharging the plurality of 50 streams of gaseous and solid carbon dioxide to the atmosphere.

2. The method of employing carbon dioxide as a fire extinguishing medium which comprises permitting sudden expansion of liquid carbon dioxide to produce a mixture of gas and snow, permitting said mixture to flow in stream form, subjecting the flowing mixture to the shock of impingement and a change in direction of travel to produce additional snow, admitting air to said 60 mixture while it is still flowing at a velocity sufficient to entrain the air, and finally discharging the gaseous and solid carbon dioxide to the atmosphere.

3. The method of employing carbon dioxide as a fire extinguishing medium which comprises discharging liquid carbon dioxide and constricting 65 said carbon dioxide at its point of discharge, permitting sudden expansion of the discharged liquid to a sufficient extent to produce a mixture of gas 70 and small particles of snow, dividing the mixture of gas and snow into a plurality of circumferentially spaced, smaller diametered, separate streams, subjecting the mixture while in said divided streams to the shock of impingement and 75

to a sharp change in direction of travel to produce large flakes of snow and to cause said streams to flow in separate, parallel paths, and finally discharging the plurality of separate streams of gaseous and solid carbon dioxide to the atmosphere.

4. The method of employing carbon dioxide as a fire extinguishing medium which comprises discharging liquid carbon dioxide and constricting said carbon dioxide at its discharge point, permitting sudden expansion of the discharged liquid to produce a mixture of gas and small particles of snow, dividing the mixture of gas and snow into a plurality of flowing streams, subjecting the mixture in said streams to a sharp change in direction of travel to produce large flakes of snow, admitting air to said flowing streams for entrainment by said mixture, and finally discharging the plurality of streams of gaseous and solid carbon dioxide to the atmosphere.

5. The method of employing carbon dioxide as a fire extinguishing medium which comprises discharging liquid carbon dioxide and constricting said carbon dioxide at its discharge point, permitting sudden expansion of the discharge liquid to produce a mixture of gas and small particles of snow, dividing the mixture of gas and snow into a plurality of flowing streams, subjecting the mixture in said streams to the shock of impingement to produce large flakes of snow, admitting air to said flowing streams for entrainment by said mixture, and finally discharging the plurality of streams of gaseous and solid carbon dioxide to the atmosphere.

6. The method of employing carbon dioxide as a fire extinguishing medium which comprises permitting sudden expansion of liquid carbon dioxide to produce a mixture of gas and snow, permitting said mixture to flow in stream form, subjecting the flowing mixture to a change in direction of travel to produce additional snow, admitting air to said mixture while it is still flowing at a velocity sufficient to entrain the air, and finally discharging the gaseous and solid carbon dioxide mixture to the atmosphere.

7. The method of employing carbon dioxide as a fire extinguishing medium which comprises permitting sudden expansion of liquid carbon dioxide to produce a mixture of gas and snow, permitting said mixture to flow in stream form, subjecting the flowing mixture to the shock of impingement to produce additional snow, admitting air to said mixture while it is still flowing at a velocity sufficient to entrain the air, and finally discharging the gaseous and solid carbon dioxide mixture to the atmosphere.

8. In fire extinguishing apparatus, a discharge head forming an expansion chamber having a small inlet orifice, a hollow drum in open communication with the chamber of said head, said drum having a plurality of circumferentially spaced discharge openings, and a plurality of elongated guide vane members, each one of which forms a passageway for a discharge opening, said members being grouped around the periphery of the drum and extending longitudinally thereof.

9. In fire extinguishing apparatus, a discharge head forming an expansion chamber having a small inlet orifice, a hollow drum in open communication with the chamber of said head, said

drum having a plurality of circumferentially spaced, peripheral discharge slots, and an elongated guide vane overlying each of said slots and extending beyond the end of the drum.

10. In fire extinguishing apparatus, a discharge head forming an expansion chamber having a small inlet orifice, a hollow drum in open communication with the chamber of said head, said drum having a plurality of circumferentially spaced, peripheral discharge slots, and an elongated guide vane overlying each of said slots and extending beyond the end of the drum, said guide vanes being so shaped and arranged with respect to their slots as to provide an impingement for and effect a change in the direction of flow of the fluid discharged from said slots.

11. In fire extinguishing apparatus, a discharge head forming an expansion chamber having a small inlet orifice, a hollow drum in open communication with the chamber of said head, said drum having a plurality of discharge openings, a guide vane for each discharge opening, and means for admitting air to each one of said guide vanes.

12. In fire extinguishing apparatus, means forming an expansion space for liquid carbon dioxide and having a small inlet orifice and a plurality of discharge openings, diffusing means in said space for directing the fluid admitted to said space through said discharge openings, means associated with said openings for forming the fluid discharged therefrom into a plurality of streams, and means for admitting air to each one of said streams formed by said last mentioned means.

13. In fire extinguishing apparatus, a discharge head forming an expansion chamber having a small inlet orifice, a hollow drum in open communication with the chamber of said head, said drum having a plurality of peripheral discharge slots, an elongated guide vane overlying each of said slots and extending beyond the end of the drum, and means for admitting air to each one of said guide vanes.

14. In fire extinguishing apparatus, means forming an expansion space for liquid carbon dioxide and having a plurality of discharge openings and a small inlet orifice, diffusing means in said space for directing the fluid admitted to said space through said discharge openings, means associated with said openings for forming the fluid discharged therefrom into a plurality of streams, for providing impingement surfaces against which said streams strike and for effecting a change in the direction of flow of each stream, and means for admitting air to each one of said guide vanes.

15. In fire extinguishing apparatus, a discharge head forming an expansion chamber having a small inlet orifice, a hollow drum in open communication with the chamber of said head, said drum having a plurality of circumferentially spaced discharge openings, diffusing and deflecting means in said drum for directing the material admitted to the hollow drum through the inlet orifice through said discharge opening, and a plurality of elongated guide vane members, each of which forms a passageway for a discharge opening, said members being grouped around the periphery of the drum and extending longitudinally thereof.

HARRY ENSMINGER.
